CLAIM

The ornamental design for tap hand cover, as shown and described.

DESCRIPTION

FIG. 1 is a top plan view of a tap hand cover;

FIG. 2 is a side elevational view thereof;

FIG. 3 is a front elevational view thereof;

FIG. 4 is a rear elevational view thereof; and,

FIG. 5 is a bottom plan view thereof.

The broken lines in the drawings illustrate portions of the tap hand cover that forms no part of the claimed design.
